UNITED STATES PATENT OFFICE.

HUGH STEVENSON, OF NEW YORK, N. Y.

ANIMAL-BED.

SPECIFICATION forming part of Letters Patent No. 424,143, dated March 25, 1890.

Application filed May 22, 1889. Serial No. 311,706. (No model.)

To all whom it may concern:

Be it known that I, HUGH STEVENSON, of the city, county, and State of New York, have invented a new and Improved Animal-Bed, of 5 which the following is a full, clear, and exact description.

This invention relates to animal-beds, and more particularly to horse-beds, the main objects of the invention being to provide a durable, dry, and at the same time comfortable bed, and one which may be used with or without the ordinary straw-bedding.

To the ends above set forth the invention consists, essentially, of a series of united tubes, 15 each of said tubes being formed with a number of practically air-tight chambers or compartments, all as will be hereinafter more fully described, and specifically pointed out in the claims.

Reference is to be had to the accompanying drawings, forming a part of this specification, in which similar letters of reference indicate corresponding parts in all the figures.

Figure 1 is a plan view of my improved 25 animal-bed. Fig. 2 is a side view of the bed; and Fig. 3 is an enlarged cross-sectional view, the view being taken on line $x-x$ of Fig. 2.

In constructing the bed forming the subject-matter of this application I employ a 30 number of elastic tubes 10, that are formed with practically air-tight chambers a , the tubes being arranged side by side and held to place by strips 11 and binding strips 12. The tubes 10 are preferably made of rubber and the

compartments a may be formed by means of 35 proper molds, in which the tubes are put at the time when the rubber is vulcanized; or the compartments may be formed after the tubes have been vulcanized by drawing the binding-strips down tight, as will be readily 40 understood. As the tubes 10 are flattened to form the compartments a , they assume substantially the form shown in Fig. 1, and consequently there are spaces between the tubes, such spaces providing for a thorough ventilation, and for the passage of urine or other 45 liquid.

Having thus described my invention, what I claim as new, and desire to secure by Letters Patent, is—

1. A bed comprising a series of united hollow parallel structures, divided transversely throughout their lengths to form a series of aligned cushions, the several series of cushions being spaced apart by aligned openings, 55 substantially as set forth.

2. A bed consisting of a number of united parallel-spaced tubes, each tube being divided into a number of practically air-tight compartments, substantially as described. 60

3. A bed made up of a number of united tubes that are divided into air-tight compartments, spaces being left at points between the tube-faces, substantially as described.

HUGH STEVENSON.
